(57) **CLAIM**

The ornamental design for an ornamental cover for a beverage container, as shown and described.

DESCRIPTION

FIG. 1 is a perspective view of an ornamental cover for a beverage container showing my new design in an installed position;

FIG. 2 is a sectional view thereof taken along line 2—2 of FIG. 1;

FIG. 3 is an exploded perspective view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front elevational view thereof; and,

FIG. 9 is a back elevational view thereof.

The portion shown in broken lines are included for illustrative purpose only and form no part of the claimed design.
